UNITED STATES PATENT OFFICE

WILLIAM GENTRY SHELTON, OF ST. LOUIS, MISSOURI

HAIR WAVING APPARATUS

Application filed June 26, 1931. Serial No. 547,104.

This invention relates to hair waving apparatus and consists particularly in a novel hair waving heater machine of the type illustrated in Patent 1,666,266, issued April 5 17, 1928, in my name.

This patent discloses a heater dome having a rectangular inner panel member for plugging in a plurality of heater cord terminals and also having a circular outer wall fitted 10 with cord holders or lifts, each having spaced rings through which the heater cord passes, the rings being arranged to hold the cord, and heater suspended therefrom, at any desired height.

15 The present invention has for its main object the provision of a simplified compact heater dome which will include many of the advantageous features of the above apparatus as well as others not obtained therein.

20 Another object is to provide a device which will include a connecting plug and cord holder or lift device in a single unit.

These general objects and other detail objects are attained in the apparatus illustrated 25 in the accompanying drawings in which—

Figure 1 is a side view of the apparatus sectioned in part.

Figure 2 is a top view of the same with portions of the dome broken away.

30 Figure 3 is a detail vertical section taken substantially on the line 3—3 of Figure 2.

The apparatus is supported on a standard 1 which has a circular sheet metal dome 2 extending substantially at right angles thereto. A ring-like panel member 3 of bakelite or other insulating material is suspended from dome 2 by bolts 4 and has a pair of vertically spaced metal strips 6 secured to the inner surface thereof by rivets 5. Extending 35 transversely through member 3 at regular intervals are a series of perforations 7 having enlarged outer portions, the inner portions thereof being provided with metal bushings 8 each of which contacts with one of the strips 6 and forms an outlet terminal. Bushings 8 are spaced from the outer surface of member 3 as shown in Figure 3. A two conductor current supply cable 9 extends upwardly through standard 1 and through an opening 10 in member 3 and connects with the strips 6.

The heaters 11, of any suitable design, are suspended on cords 12, each of which closely fits within an opening 13 in the corresponding plug block 14. The blocks 14 are preferably formed of two parts secured together by 55 screws 15, and each has an opening 18 for receiving the end of cord 12. Prongs 16 are provided with screws 17 for connection with the cord. Projecting portions 19 on the plug blocks are slightly wider than the enlarged 60 outer portions of perforations 7 so that blocks will seat against the outer surface of member 3. Any desired number of heaters may be operated from the machine by utilizing additional pairs of terminal openings or sockets 7 65 and the number of the terminals may be varied according to particular requirements.

The frictional engagement between opening 13 in the plug block and cord 12 is sufficient to hold the cord in any position at which it is placed by the operator and to cause the corresponding heater to be supported at the desired height.

While a single circuit apparatus in which current is supplied to all heaters at the same 75 time is shown, the machine can readily be arranged for two or more circuits permitting groups of heaters to be operated separately. In the latter case, proper switch facilities would be necessary which could be operated 80 separately from a main switch, preferably mounted on the standard.

Moreover, each plug block 14 could be modified to accommodate two or more heaters by the provision of one or more additional 85 cord gripping openings, corresponding with opening 13, and means for connecting the additional wire or wires with prongs 16. If desired, the individual heater cords could be inserted through a suitable opening in a lug or other protuberance on the plug block instead of through the block itself, and spring engagement could be provided between the cord and the block which would decrease the wear 90 on the cord and provide for varying the resistance to the movement of the cord through the lift device.

Obviously, certain other details of the embodiment shown and described such as the shape and size of the various parts, etc., might 100

be modified without departing from the spirit of the invention, and I contemplate the exclusive use of all such modifications as come within the spirit of my invention.

6. What is claimed is:

1. In a hair waving machine, a support, a closed wired member secured thereto, outlet terminals in said member adapted to be connected with the terminals of a heater cord, and a lift element mounted on said member and adapted to directly support said cord and yieldingly maintain the same in a desired position.

15 2. In a hair waving machine, an overhead dome having a closed wired member suspended therefrom, outlet terminals in said member adapted to be connected with the terminals of a heater cord, and a lift element mounted on said member and adapted to directly support said cord and yieldingly maintain the same in a desired position.

25 3. In a hair waving machine, a dome, a continuous member of insulating material depending therefrom, spaced conductors extending around the periphery thereof, means for connecting said conductors with a source of current, outlet terminals in said member adapted to be connected with the terminals of a heater cord, and a lift element mounted on said member and adapted to yieldingly grip said cord to maintain the same in a desired position.

20 4. In a hair waving machine, a dome having a continuous vertical surface, and a heater cord plug and a lift element for said cord mounted on said surface.

25 5. A plug for attaching an outlet cord for an electric unit to a source of current and including a lift element for yieldingly gripping said cord to maintain said heater at a desired distance from said plug.

40 6. A plug for attaching an outlet cord for an electric unit to a source of current and comprising a body portion, spaced contacts on said body portion adapted to be connected with an end of said cord, and a recess in said portion shaped to receive a portion of said cord spaced from said end and to yieldingly resist its passage therethrough.

50 7. A plug for attaching an outlet cord for an electric unit to a source of current and comprising a body portion, spaced contacts on said body portion adapted to be connected with an end of said cord, a recess in said portion shaped to receive a portion of said cord spaced from said end and to yieldingly resist its passage therethrough, and prongs projecting from said body portion for connection to a suitable socket member.

55 8. In hair waving apparatus, a dome including a continuous upright surface, conductors extending along said surface, outlet terminals in said surface, and a combination heater cord plug block and cord lift member detachably engaging said terminals.

9. In hair waving apparatus, a dome, a non-conducting member extending around the periphery thereof, spaced electrical conductors in said member, means connecting said conductors with a current supply, outlet terminals in said member and engaging said conductors, and a plurality of heaters having wire cords and plug blocks for connection with said terminals, each block including a lift element yieldingly gripping the corresponding cord and serving to maintain the heater at a desired distance from said dome.

In testimony whereof I hereunto affix my signature this 23rd day of June, 1931.

WILLIAM GENTRY SHELTON.
